UNITED STATES PATENT OFFICE.

FRED A. CUTBURTH, OF WICHITA, KANSAS.

BOTTLE-CARRIER.

1,355,214.

Specification of Letters Patent.

Patented Oct. 12, 1920.

Application filed January 7, 1920. Serial No. 349,907.

To all whom it may concern:

Be it known that I, FRED A. CUTBURTH, a citizen of the United States, residing at Wichita, in the county of Sedgwick and 5 State of Kansas, have invented certain new and useful Improvements in Bottle-Carriers, of which the following is a specification.

This invention relates to improvements in 10 supports and more particularly to a device especially adapted for carrying bottles.

An important object of this invention is to provide a bottle carrier including a split band adapted for engaging the neck of a bottle 15 directly below the bead of the same and having novel means whereby the band may be readily and securely attached.

A further object of the invention is to provide a carrier for milk bottles which is simple, desirable in use and cheap to manufacture.

A further object of this invention is to provide a carrier for milk bottles which when applied will not interfere with the filling of the bottle or dispensing the contents 25 of the same and which will greatly convenience the pouring of the milk or other contents from the bottle.

Other objects and advantages of the invention will be apparent during the course 30 of the following description.

In the accompanying drawing, forming a part of this application and in which like numerals are employed to designate like 35 parts throughout:

Figure 1 is a fragmentary perspective view of a milk bottle having the improved carrier applied thereto,

Fig. 2 is a fragmentary elevation of the 40 milk bottle having the carrier applied, and

Fig. 3 is a perspective of the carrier detached.

In the drawing wherein for the purpose 45 of illustration is shown a preferred embodiment of the invention, the numeral 5 generally designates a milk bottle having a neck 6 and the usual annular bead 7. A cap or disk 8 may be applied to the bottle for closing the upper end of the same after the 50 bottle has been filled.

Specifically, this invention includes a split band 9 adapted to be arranged about the neck of a bottle directly beneath the bead of the 55 same and is preferably formed from a light flat strip of metal. When the band 9 is arranged about the bottle neck in engagement

with the bead 7 of the same, the end portions 10 and 11 of said band are overlapped so as to permit a U-shaped keeper or staple 12 carried by one end portion of the band to 60 be extended through a transversely extending slot or opening 13 in the end portion 11 for joining the ends of said band. The intermediate portion of the split collar or band 9 is provided on its outer side with a U- 65 shaped bracket or attaching device 14 to which one end of a U-shaped bail 15 is connected. As illustrated in Fig. 2, the said end portion of the U-shaped bail 15 is provided with a loop 16 extended through the 70 bracket or staple 14 so that the bail will be nondetachably secured to the band.

With reference to Fig. 3, it will be noted that the opposite end portion of the bail is bent upon itself to provide a loop 17 adapted to be detachably connected with the U-shaped keeper or staple 12. The free end portion of the loop 17 is extended outwardly as indicated at 18 for forming a tapered 75 guide for one arm of the keeper 12 and is then extended inwardly into contact with the other side of the loop for forming a retaining shoulder 19. The retaining shoulder 19 coacts with the adjacent portion of the bail for normally closing the loop 17 so 80 that it is necessary to spring the free end portion 18 of the loop outwardly when it is desired to connect the loop 17 with said keeper.

When it is desired to apply the improved 90 carrier to a bottle, the band is arranged about the neck in engagement with the under side of the bead 7. By reason of the band being split, the end portions of the same may be readily overlapped to permit of the insertion of the keeper 12 through the transverse opening 13. After the keeper 12 has been inserted through the opening 13, the loop 17 is engaged with said keeper by moving the bail downwardly and upwardly. As 100 the loop is engaged with the keeper, the free end portion 18 of the loop is sprung outwardly to provide an entrance opening for the keeper. When one arm of the keeper is received within the loop, the shoulder 18 105 will close the entrance opening to the loop so that the accidental disconnection of the bail with the keeper will be prevented. By this construction the keeper 12 serves a dual function which is: first, as a locking device 110 for the ends 10 and 11, and secondly, as an attaching member for one end of the bail.

In use, the device serves as a convenient means for carrying the bottle from one place to another and if desired may remain attached to the bottle. However, by reason 5 of the fact that the carrier may be readily detached from the bottle, the same does not interfere with the convenient cleaning of the bottle or refilling of the same. The carrier also serves as a means of conveniently 10 pouring the milk from the bottle since the bail may be manually gripped for supporting the neck of the bottle when the bottle is being tipped.

It is to be understood that the improved 15 carrier may be applied to other bottles than milk bottles and also that such minor changes in arrangement and construction of parts may be made as will remain within the spirit of the invention and the scope of 20 what is claimed.

Having thus described the invention, what is claimed as new is:

1. A carrier for milk bottles including a split band formed from an elongated length 25 of flat metal, a keeper carried by one end portion of the split band, the other end portion of the split band being provided with an opening receiving said keeper, a bail having one end portion attached to the intermediate portion of the band and its other 30 end portion detachably connected to said keeper whereby the end portions of the band are detachably connected.

2. A carrier for milk bottles including a split band having its end portions overlapped, a keeper carried by one end portion of the band, the other end portion of the band being provided with an opening receiving said keeper thereby connecting the end portions of the band, and a bail having one 40 end portion attached to the intermediate portion of the band and its other end portion provided with a loop adapted for connection with said keeper for securely retaining said keeper extended through said opening.

3. A bottle carrier including a split band having its end portions overlapped, a keeper carried by one end portion of the band and extended through the other end portion of the band, and a bail having one end portion bent upon itself for forming a loop, one side of said loop being extended inwardly in contact with the other side of the loop for forming a restricted entrance opening, 55 said loop having one side extended outwardly beyond said entrance opening for forming a guideway for said keeper.

4. A bottle carrier including a split band, a keeper carried by one end of the band and 60 detachably connected with the other end of the same, and a bail having one end portion secured to said band and its other end portion detachably connected to said keeper.

In testimony whereof I affix my signature. 65
FRED A. CUTBURTH. [L.S.]
